UNITED STATES PATENT OFFICE.

HARRY C. HOWER, OF CHICAGO, ILLINOIS.

DESIGN FOR AN AUTOMOBILE TIRE.

Application filed September 23, 1922. Serial No. 3,807. Term of patent 14 years.

To all whom it may concern:

Be it known that I, HARRY C. HOWER, a citizen of the United States, residing at Chicago, in the county of Cook and State of Illinois, have invented a new, original, and ornamental Design for Automobile Tires, of which the following is a specification, reference being had to the accompanying drawing, forming a part thereof.

Fig. 1 is a plan view of a portion of the

tire;

Fig. 2 is a side elevation of the same; and

Fig. 3 is a transverse radially disposed section on the line 3—3 of Fig. 1.

I claim:

The ornamental design for an automobile tire, as shown.

HARRY C. HOWER.
